RATCHET GEAR ASSEMBLY FOR WRENCHES

Filed June 20, 1947

UNITED STATES PATENT OFFICE

2,559,332

RATCHET GEAR ASSEMBLY FOR WRENCHES

Roy O. Wright, Huntington, W. Va.

Application June 20, 1947, Serial No. 755,979

2 Claims. (Cl. 81—56)

1

This invention relates to improvements in wrenches, and more particularly to improvements in the wrench shown and described in Patent 2,181,678.

The improvements to be later described alter in no way the principal object of the invention covered by the above patent which includes the engaging of a pair of threaded elements whereby to secure one of said elements stationary, while the other of said elements is actuated for adjustment, attachment or detachment, relative to the first element.

This invention, however, does provide improvements in the general physical character of the wrench effecting means whereby more simple construction, durable usage, effective operation and more economical manufacture is obtained.

Other objects and advantages, however, will be apparent from the following description, when taken in conjunction with the annexed drawings in which:

Figure 1 is a longitudinal sectional view of an embodiment of the invention;

Figure 2 is a front elevational view thereof partly broken away to show the internal moving parts thereof;

Figure 3 is a rear elevational view thereof partly broken away and partly in section and

Figure 4 is a sectional view of the floating socket.

Referring more in detail to the drawing, the reference numeral 10 designates a barrel or elongated tubular casing formed with a longitudinally extending bore 11 which communicates at one end with hexagonal shaped bearing socket 12 and at the other end with the enlarged circular socket 13 on the end of which the enlarged hexagonal shaped socket 14 is provided. The interior of the socket 12 has an inside square shaped socket 12' which communicates with the bore 11, while the exterior surface of the socket 13 is shaped for engagement with the jaws of a wrench. The inner face of the socket 14 is hexagonal in formation, as shown at 15, to receive a nut or head of a bolt or stud or a wrench or similar tool.

A prying lever or shaft 16, of a substantially elongated cylindrical configuration is detachably and rotatably secured in the bore 11, and the shaft is provided at one end with a cylindrical shaped head 17 seated within the socket 13 and having an inclined face 18 abutting the similarly contoured shoulder 19 of the socket 13, and the head 17 is fashioned with a nut receiving socket 20. The opposite end of the shaft 16 extends an appreciable distance beyond the end of the barrel 10 and is formed with an arcuate cuneiform shaped end 21 whereby the elements previously described may be used as a pry, all of which is covered by the patent previously mentioned.

The improvements to the already patented construction consist of fashioning the lever or

2

shaft 16 inwardly of the end 21 in a square shaped formation 22 and mounting thereon a sleeve 23 having a longitudinal bore 24 therein to conform to the shape of the formation 22.

5 The forward end of the sleeve 23 is fashioned in a square shaped formation 24 to receive a wrench for the turning thereof as desired, and inwardly of the formation 24, a transverse opening 25 is provided to receive a bar or other means 10 for rotating the sleeve and inwardly of the opening 25 a set screw 26 in the sleeve retains the sleeve in fixed relation to the lever 16.

Mounted on the lever 16 is a gear housing 27, the rear wall 28 of which abuts the forward end 15 of the socket 12, and surrounding the opening 29 in the wall 28, through which the lever 16 extends forwardly thereof is a hub 30. Mounted on the socket 12, within the hub 30, by means of a central hex shaped bore 31, is the floating

20 collar 32, having longitudinal grooves or ratchet teeth 33 in the outer periphery thereof. The collar 32 is retained in the hub 30 by the ring plate or cover 34 secured to the hub 30 by the screws 35. Extending outwardly from the hub 30 at right angles thereto, is a cylindrical casing 36 in which is mounted the trigger pawl or ratchet 37 on the stem 38 on which is mounted a spring 39, and a nut 40 threadably connected to the cylindrical casing 36 tensions the ratchet 30 pawl 37 to force the pawl into the teeth 33 of the collar 32.

Secured to the upper end of the stem 38 of the pawl by a pin 41 is a knob 42 and a pin 43 mounted transversely of the stem 38 below the 35 knob 42 is receivable in the transverse slot 44 in the top of the nut 40.

The pawl or ratchet is so shaped, as shown in Figure 3, that the collar 32 will rotate in one direction only, but the pawl can be pulled upwardly against the tension of the spring 39 and reversed so that the rotation can be made in the opposite direction. The pin 43 acts as a guide to properly position the pawl after it has been rotated, and also holds the pawl in fixed relation to the nut and housing 36.

The face of the wall 28 opposite to the hub 30 is provided with a recess 45 formed by the outwardly projecting ring formation 46, and the inner end of the sleeve 23 is receivable in this 50 recess and has a socket 47 to engage the lever 16 at the end of the formation 22.

The portion 48 of the sleeve 23 is square in formation to receive the large gear 49, and a circular shoulder 50 on the sleeve abuts the gear 55 55 49 on one side thereof and key slot 51 in the portion 48, receives a key 52 to fix the gear to this portion.

Secured to the housing 27 by screws 53 is a face plate 54 of similar contour and the wall 28 60 is provided with an opening 55 in alignment with an opening 56 in the face plate 54 to journal a stub shaft 57 therein.

The shaft 57 has a key slot 58 therein to receive a key 59 whereby a pinion 60 is fixed thereon for engagement with the gear 49, thus providing a ratchet gear assembly.

One end of the shaft 57 is threaded as at 61 to receive the lock washer 62 and lock nut 63, which is fixed thereto in the conventional manner by having a cotter key passing through the opening 64 in the nut 63, and the opening 65 in the threaded end 61, when said openings are in alignment with each other. The opposite end of the shaft 57 is provided with a circular portion 66 on which is formed centrally thereof, the square shaped head 67 which is so designed as to receive a wrench or the like to rotate the pinion 60 and an opening 68, transversely of the portion 66, will receive a bar or other means for the rotation of the pinion 60.

The ratchet gear assembly thus described, when used in conjunction with the wrench previously described, will rotate the wrench as desired.

The gear assembly pry or lever 16 and barrel or tubular casing 10 are all detachable one from the other for separate use thereof as desired.

In use, with the sockets 14 or 17 engaged with a nut depending on the size thereof, since the lever 16 can be moved longitudinally to permit engagement of the socket with a nut, the sockets are rotated by the application of a wrench to the ends 24 or 67, and one or two nuts can be loosened or tightened at the same time by engagement of the end 24 with a nut. The lever 16 may be held stationary while the barrel 10 is rotated to effect reverse adjustment between two nuts. The interior socket 12' of the socket 12 permits pulling the gear assembly forward to free the barrel 10 from one nut. Thus the square end 22 of the pry 16 will be in contact with the socket 12', so that the inner wrench can be rotated with the ratchet. The socket 12' can also be used advantageously when the device is used separately from the gear assembly. Thus nuts of various sizes may be adjusted simultaneously in reverse or similar direction to each other. The sockets may be made to conform to other shapes than those described, without departing from the spirit of the invention.

From the foregoing, it will be apparent that there has been provided a simple and efficient wrench, so constructed and arranged as to permit relative adjustment of a pair of nuts without the use of additional means for securing one of said nuts stationary relative to the other during a desired adjustment.

It is also to be distinctly understood that various changes and modifications in the construction and arrangement of the various parts may be resorted to, provided they fall within the spirit of the invention and the scope of the appended claims.

Having thus described the invention, what is claimed as new and desired to be secured by Letters Patent is:

1. In a dual socket wrench, the combination which comprises a gear housing having a hub extended from one side thereof, an elongated tubular casing having a collar with radially disposed teeth in the outer surface on one end and having a nut receiving socket in the opposite end, said elongated tubular casing extended from the gear housing and positioned with the collar thereof journaled in the hub extended from the side of the housing, a cylindrical casing extended radially from one side of the hub, a ratchet in

the said cylindrical casing positioned to coact with the teeth of the collar of the elongated tubular casing and having a stem with a nut on the outer end slidably mounted in the said cylindrical casing, a spring on said stem for urging the ratchet into engagement with the teeth of the collar, said ratchet mounted to be rotated by the nut on the outer end of the stem through an angle of 180 degrees to reverse the direction of rotation the tubular casing may rotate in the hub, a prying shaft journaled in the said elongated tubular casing and extended through and beyond the gear housing, said prying shaft having a nut receiving socket in the end thereof positioned in the end of the tubular casing in which the said nut receiving socket thereof is positioned, said nut receiving sockets of the casing and prying shaft being aligned with the axis of the shaft and tubular casing, a sleeve mounted on the portion of the shaft extended beyond the said gear housing, a gear positioned in the gear housing and mounted on the said sleeve, said sleeve having wrench gripping surfaces thereon and openings therein, a stub shaft journaled in the gear housing and also having wrench gripping surfaces on an extended end thereof and openings therein, said stub shaft positioned parallel to and spaced from the said prying shaft, and a pinion positioned in the gear housing meshing with the gear on the sleeve on the prying shaft and mounted on the said stub shaft.

2. A ratchet gear assembly for a wrench of the type having a barrel and a shaft rotatable in the barrel, the barrel and shaft being provided at their forward ends with actually aligned sockets of different sizes and relatively spaced axially of the wrench, and the shaft being extended rearwardly beyond the barrel, the ratchet gear assembly comprising a housing, a bearing on the forward side of the housing, a sleeve journaled in the housing in axial alignment with the bearing and extending rearwardly from the housing, a collar nonrotatably mounted on the rearward end of the barrel and rotatably mounted in the bearing, the collar being provided in its outer side with ratchet teeth, the rear end of the shaft being located in the sleeve, means connecting the shaft and sleeve to adapt the former to impart rotation to the collar, a spring loaded pawl carried by the bearing and operating with the ratchet teeth to hold the collar against movement in one direction, a gear within the housing fixed to the sleeve, a shaft rotatable and extending rearwardly beyond the housing, a pinion fixed to the shaft meshing with the gear, the outer end of the sleeve and said second shaft being constructed to adapt one or the other to be turned by a tool.
